UNITED STATES PATENT OFFICE.

JOHN ANDERSON, OF WEST MOUNT VERNON, MAINE, ASSIGNOR OF ONE-HALF TO G. L. WINTHROP, OF TALLAHASSEE, FLORIDA.

AEROPLANE.

1,054,484.

Specification of Letters Patent. Patented Feb. 25, 1913.

Application filed November 8, 1912. Serial No. 730,179.

To all whom it may concern:

Be it known that I, JOHN ANDERSON, a citizen of the United States, and a resident of West Mount Vernon, in the county of Kennebec and State of Maine, have invented a new and Improved Aeroplane, of which the following is a full, clear, and exact description.

Among the principal objects which the present invention has in view are: to provide carrying planes constructed to give a maximum strength and rigidity with minimum weight; to provide a carrying structure manually controlled to effect a proper balance of the machine; to provide means for facilitating the banking of the machine when turning a curve, or to regain its equilibrium; to provide a car arranged to protect the aviator and motor with the least retardation of the flight; to provide an inclosed casing for the motor employed in conjunction with the aeroplane, having an exhaust duct opening at the rear of the machine to convey the sound of the exhaust away from the aviator; to provide a suitable and convenient skid for supporting the machine when on the ground; to provide a car body shaped to the wave line of flight to avoid the suction at the rear of a fast moving body.

Reference is to be had to the accompanying drawings forming a part of this specification in which like characters indicate corresponding parts in all the views and in which:

Figure 1 is a top plan view of an aeroplane constructed and arranged in accordance with the present invention, a segment of the upper cover of the plane being removed to show the rib and cross-brace construction thereof. Fig. 2 is a front elevation of the same, the carrying planes being exposed in a horizontal position. Fig. 3 is a similar view, showing the carrying plane as tilted from the horizontal. Fig. 4 is a vertical cross-section on an enlarged scale, taken on the line 4-4 in Fig. 1. Fig. 5 is a top plan view of the aviator's car, a portion of the frame whereof is cut away to show the construction within the car. Fig. 6 is a detail view on an enlarged scale in vertical cross sections, taken in line 6-6, Fig. 4. Fig. 7 is a cross section on a large scale taken on the line 7-7 in Fig. 4. Fig.

8 is a vertical cross section on the line 8-8 in Fig. 4, showing the car body and a fragment of the carrying plane. Fig. 9 is a detail view on an enlarged scale, showing a vertical, longitudinal section taken on the line 9-9 in Fig. 1. Fig. 10 is a detail view in vertical cross section taken on the line 10-10 in Fig. 9, showing a fragment of the carrying plane structure. Fig. 11 is a detail view in perspective, showing the outer and free corner of the warping sections with which the aeroplane is provided.

As seen in the drawings, the invention is shown in its adaptation to an aeroplane of the class known as monoplane. The invention adapts itself most readily to this style of aeroplane, but it will be understood that it may also be adapted to structures having two or more carrying planes.

In all designs it is preferred that the top or main plane shall be provided with the transverse, tubular braces 15. The braces 15, as shown best in Figs. 1-3 of the drawings, are tapered from the largest diameter at the center of the carrying plane upward to the ends of the carrying plane, thereby accommodating the structure to what may be termed truss strains. The tubular form of the braces adapts the structure to horizontal as well as vertical strains. Auxiliary to the braces 15 is employed a frame 16, upon which are converged, and to which are secured, the tapered ends of the ribs 17 and 18, forming the skeleton of the main plane. The frame 16 is triangular in cross section, as seen best in Fig. 3 of the drawings, and is molded or shaped to a graceful line to form the forward edge of the plane, substantially as shown in Fig. 1 of the drawings. At the lateral extremes of the main plane the ends of the frame 16 are trailed off to the rear to form the end rib of the skeleton upon which is stretched the usual covering 19 and 20, which is preferably constructed from light duck, silk or other suitable material. The ribs 17 and 18 are secured fixedly to the braces 15. The braces 15 pass through perforations provided in a hollow keelson 21 with which the structure is provided, as best seen in Fig. 4 of the drawings. The braces 15 and the frame 16 are fixedly secured in said keelson.

It will be noted that the construction and arrangement of the parts forming the skel-

2
eton of the carrying plane herein shown provides for a relatively rigid median section and relatively flexible extremes for the said carrying plane. To augment the flexibility 5 of the plane structure the ribs 18 are constructed of laminated strips of wood separated at the rear of the braces 15, or, if constructed from a single piece of wood, the same is sawed scarfed to form spaces 22 between the sections of the said ribs. At the 10 end of each of the upper strips is placed a bracket 23, the upper end of which is rounded to form a nosing to rest under the rib 17, companion to the rib 18, thus constructed. This arrangement affords a structure 15 which readily yields to varying air pressures imposed upon the plane either above or below the same.

At the outer edge of each plane and at 20 the rear of the transverse median line thereof is provided a warping section overlaid upon the covering 19 of the main plane. The warping section 24 is suitably ribbed to shape the same to normally rest upon the 25 covering 19 of the main carrying plane. The ribs provided for this purpose are preferably rigidly connected at their forward ends with the covering 19 upon which they normally rest.

30 It will be understood that the normal tendency of the ribs incorporated in section 24 operate to close the said section closely upon the cover 19. To hold said section in the normal position, against accidental dislodgment therefrom, I provide a latch 25, which is pivotally mounted at 26 upon a bracket 27. Bracket 27 is mounted upon the rib of the section 24 disposed at the extreme of the carrying plane. The 35 head 28 of the latch 25 extends below the rib 18 and cover 20 thereof. See Fig. 9. The latch is normally held in locking position by the spring 29. From this position it is moved by the light cable 30, which is 40 primarily drawn upon when it is desired to warp the plane by lifting the section 24 at either end of the said plane.

The levitation of the aeroplane in flight is 45 controlled by a tail plane 31. The plane 31 is preferably integrally formed with the keelson 21, and, like the keelson, is constructed in hollow form. The plane 31 is rarely flared or fanned, as seen best in Fig. 1 of the drawings. The sides of the plane 31 55 are slightly spread or separated at the rear-most edge to reinforce the construction and to receive the eyelets 32. As seen in Fig. 1 of drawings, eyelets 32 are separated to receive in spread arrangement the sling cables 33, which converge forwardly and are secured to the ring 34, to which is also connected the cable 35, employed for lifting the 60 rear end of the tail plane 31 when operated to that effect by the aviator.

65 The rear end of the tail plane 31 is de-

pressed by the aviator operating the cable 36, which draws upon the eyelets 32 at the under side of the plane 31, being connected therewith by the sling cables 37 and the connecting ring 38. The cables 35 and 36 are 70 elevated from the normal plane of the plane 31 to facilitate the operation described by the pulleys 39 and 40 respectively. The pulleys 39 and 40 are rotatively mounted in 75 housings 41 and 42 formed at the junction of the keelson 21 and tail plane 31. See Figs. 4 and 6 of the drawings.

Intermediate the housings 41 and 42 and the rear end of the tail plane 31, the material of which the said tail plane is constructed is contracted to form the pin or resilient portion 43. It is about the portion 43 that 80 the tail plane 31 vibrates when moved thereto by the operation of the cables 35 and 36.

The cables 30, 35 and 36 are all operated 85 by the aviator when reposing on the seat 44 within the car 45. The car 45 is substantially egg shape, as shown in the drawings, the butt end of the egg shape being disposed forwardly. At the forward end of 90 the car 45 is a hinge wing 46 extending from the surface thereof and provided at the upper edge with a series of hinge knuckles spaced apart to receive corresponding hinge knuckles formed at the lower edge of the 95 keelson 21. The hinge knuckles mentioned are perforated in line to receive a hinged bolt 47. By means of this construction the car 45 is suspended from the said keelson and the carrying plane connected therewith. 100 The joint formed by the hinge knuckles is sufficiently elongated to prevent any disalignment of the car body with the carrying planes. The hinge thus formed, however, permits the car to swing laterally from 105 the keelson and planes, or the car being stationary the aviator is permitted to relatively vary the inclination of the carrying planes from the horizontal or from the perpendicular as embodying the center of gravity of the car 45. To change the relative angle of the car body and the carrying plane I provide a strut 48, which is pivoted on the hinge pin 47, to extend to near the bottom 110 of the car, where it is connected to the guy 115 lines 49 of the eyelets 50. The strut 48 is connected by the endless cable 51 to a lever 52, which is pivotally mounted in the standards 53 adjacent the aviator's seat 44. Cable 51 is threaded around pulleys 54 and 55 to 120 accommodate the fore and aft throw of the lever 52. The lever 56 is connected by means of the cable 57, which likewise is reeved about the pulleys 55 and 58, to the rocking lever 59, which lever is also pivoted on the 125 hinge pin 47 and hangs in the frame of the car 45 normally parallel with the strut 48. The upper end of the lever 59 is rigidly connected to the cables 30, which, as above 130 stated, extend to and are operatively con-

nected with the latch 25. It will thus be seen that as the aviator moves the lever 52 forward or backward the carrying plane is changed in its angular relation to the car body; the car body being held by the weight carried thereby maintains its vertical plane and the carrying planes are shifted to vary from the horizontal. It is equally evident that as the aviator moves the lever 56 forward or back the warping sections 24 are lifted from the top of the main plane, the latch 25 having been disposed to remove the head 25 from engagement with the carrying plane. As illustrating the result of the pull on the cable 30 to lift the warping section 24, attention is drawn to the dotted line construction shown in Fig. 9 of the drawings, where in dotted lines the warping section 24 is shown as raised away from and above the top of the main carrying plane.

It is desired that in lifting the warping section 24 the extreme outer and rearmost corner of the said section shall be lifted in advance of and higher than the remainder 25 of the section to form of the said section a pocket for trapping the air. With this object in view, the short connecting cables 60 are graduated, being formed successively longer in proportion as each is connected to the cable 30 nearer the center of the carrying plane. Thus it will be seen in Fig. 1 of the drawings, and at the right hand of the said figure, that in the normal 30 position of the warping section 24 the cable 30 is taut. Also that the short connecting cable 60, nearest the median line of the aeroplane, is slack, and that each connecting cable 60 intermediate the end section of the cable 30 and the inner connecting cable 60 is slack but in less degree progressively as the said connecting cable is disposed nearer the end of the cable 30. The result of this arrangement when the cable 30 is drawn 35 upon is illustrated at the left hand side of Fig. 1, where it will be seen that each of the connecting cables 60 is taut and that those nearer the end of the cable 30 and the outer edge of the warping section have drawn 40 upon the warping section connected therewith to lift the rear edge thereof, bowing the rib connected therewith substantially as shown in dotted lines at Fig. 8 of the drawings.

The operation of the warping section 45 24 is understood to independently vary the horizontal disposition of the carrying plane without varying the relative angle of the carrying plane and car body. In the present construction the lifting of the warping section at either side of the carrying plane would result in depressing that side of the carrying plane, the warping section being lifted above said planes. Thus, if in flying 50 the aeroplane shifts or loses its equilibrium

this may be righted by moving one or other of the warping planes to depress the raised end of the said carrying plane.

The sections 24 in the present construction also serve to operate as rudders. The 55 lifting of either of the sections sufficiently would result in a drag on the aeroplane at that end of the carrying plane, and which drag being resisted only by the inertia of the machine, turns the machine in its horizontal flight.

The aviator when reposing on the seat 44 rests his feet on the pedals 61 and 62. The 60 pedal 61 is connected with the cable 36, which cable it will be remembered is above 65 described as connected with the line 38 and the sling cables 37. The cable 36 is reeved over the pulleys 63, 64 and 40, as seen best in Fig. 4 of drawings. By depressing the 70 pedal 61 the aviator depresses the rear end 75 of the tail plane 31 causing the aeroplane to dip forward.

The motor 74 is of any approved conventional construction. Mounted upon the driving shaft 75 thereof is an aero-propeller 65. The motor 74 and fuel tank 66 are both contained in the chamber of the car 45 formed by the partition 67 which divides the car vertically, separating the motor and tank from the compartment occupied by the aviator. Extending from the chamber 68, which is formed by the partition 67, is an exhaust pipe or duct 69, which is seen best in Fig. 4 of the drawings, opening from the casing of the car 45 to the passage 70 formed therein, leading the duct 69 backward and carrying the fumes and sound incident to the exhaust past the aviator and rids him of much of the discomfort incident to the operation of aeroplanes 75 with high-power motors.

When on the ground the aeroplane is supported on the carrying wheels 71 and by the stilt 72, the wheels 71 and the stilt 72 forming a skid for the car which permits it to move over the ground until sufficient headway is gained to give the aeroplane its upward flight. When starting the car the aviator by depressing the tail plane 31 lifts the car sufficiently to remove the 80 supporting strain from the stilt 72 and to 85 repose the carrying weight on the wheels 71. When sufficient headway has been gained to sustain the car the aviator, by lifting the tail plane 31, inclines the carrying plane sufficiently to lift the car from the ground. When the car is free from the ground the aviator, by drawing upon the cable 73, holds the stilt 72 to the position shown in dotted lines in Fig. 4 of the drawings. When, after the flight is completed, it is desired to land, the aviator by releasing the cable 73 permits the stilt 72 to drop into vertical position where it first contacts 90 with the ground. By the engagement with 95

the ground the stilt 72 is moved upward to the position substantially as shown at Fig. 1.

Having thus described my invention, I claim as new and desire to secure by Letters Patent:—

1. In an aeroplane, and in the carrying plane thereof, the combination of a transversely-disposed tube; a keelson rigidly attached to said tube at the middle thereof; a plurality of ribs disposed transverse said tube and shaped to form upper and lower separated walls; a cover external said ribs to form the surface of said plane; a plurality of flexible cover sections overlaid on said plane at the outer edge thereof and separated from the cover of said plane at the rear edge thereof; and means for separating said cover sections from said plane to form warping sections therefor.

2. In an aeroplane, and in the carrying plane thereof, the combination of a keelson parallel with the axis of said aeroplane; a tube mounted on said keelson, perpendicular thereto, said tube being tapered in both directions from said keelson; a plurality of forming ribs disposed transverse to said tube and separated thereby to form a hollow structure; an upper and lower external covering for said ribs to form the surface of said plane; a plurality of resilient cover sections overlaid on said plane adjacent the extreme lateral ends and rear edge thereof; and means, manually operable from the station of the aviator of said aeroplane, to separate said cover from said plane.

3. In an aeroplane, and in the carrying plane thereof, the combination of a keelson parallel with the axis of said aeroplane; a tube mounted on said keelson, perpendicular thereto, said tube being tapered in both directions from said keelson; a plurality of forming ribs disposed transverse to said tube and separated thereby to form a hollow structure; an upper and lower external covering for said ribs, to form the surface of said plane; a plurality of resilient cover sections overlaid on said plane adjacent the extreme lateral ends and rear edge thereof; and means, manually operable from the station of the aviator of said aeroplane, to separate said cover from said plane, the operating means being adapted to separate the outer and rearward corner of said cover sections preliminary to separating the adjacent portions of said covering from said plane to pocket the air at the outer end of said plane.

4. In an aeroplane, and in the carrying plane thereof, the combination of a keelson parallel with the axis of said aeroplane; a tube mounted on said keelson, perpendicular thereto, said tube being tapered in both directions from said keelson; a plurality of forming ribs disposed transverse to said tube and separated thereby to form a hollow

structure; an upper and lower external covering for said ribs to form the surface of said plane; a plurality of resilient warping sections superposed on said plane at the outer end thereof, said sections being rigidly attached to said plane intermediate the forward and rear end, and separable from said plane adjacent the lateral and rear edge; and means, manually operable, for lifting said sections, said means operating primarily on said section at the rear of the lateral extreme thereof.

5. In an aeroplane, and in the carrying plane thereof, the combination of a keelson parallel with the axis of said aeroplane; a tube mounted on said keelson, perpendicular thereto, said tube being tapered in both directions from said keelson; a plurality of forming ribs disposed transverse to said tube and separated thereby to form a hollow structure; an upper and lower external covering for said ribs to form the surface of said plane; a plurality of resilient warping sections superposed on said plane at the outer end thereof, said sections being rigidly attached to said plane intermediate the forward and rear end, and separable from said plane adjacent the lateral and rear edge; an operating cable for said sections connected directly in the outer rearmost corner of said sections and operable from the aviator's car of said aeroplane; and a plurality of short cables connecting the rear edge of said sections and said operating cable, said connecting cables being elongated proportionate to their removal from the outer edge of said sections to successively tighten and lift the edge of the sections where attached.

6. In an aeroplane, and in the carrying plane thereof, the combination of a keelson parallel with the axis of said aeroplane; a tube mounted on said keelson, perpendicular thereto, said tube being tapered in both directions from said keelson; a plurality of forming ribs disposed transverse to said tube and separated thereby to form a hollow structure; an upper and lower external covering for said ribs to form the surface of said plane; a plurality of resilient warping sections superposed on said plane, at the outer end thereof, said sections being rigidly attached to said plane intermediate the forward and rear end, and separable from said plane adjacent the lateral and rear edge; an operating cable for said sections connected directly in the outer rearmost corner of said sections and operable from the aviator's car of said aeroplane; a plurality of short cables connecting the rear edge of said sections and said operating cable, said connecting cables being elongated proportionate to their removal from the outer edge of said sections to successively tighten and lift the edge of the sections where attached; a lever operatively connected with said oper-

ating cable to coincidentally draw upon one section of said operating cable and the connecting cables connected therewith while relaxing the opposite section of said operating cable and connecting cables united thereto.

7.. In an aeroplane such as described, and in the carrying plane thereof, the combination of a plurality of superposed forming ribs, one of said ribs having a plurality of 10 resilient extensions, the ends whereof bear upon the opposed rib to yieldingly maintain the separation of said ribs; framing members, one of said ribs having a plurality of tubular braces interposed between said ribs; 15 adjacent the forward end thereof to form a rigid construction at the forward edge of said plane.

8. In an aeroplane such as described, and in the carrying plane thereof; the combination of a plurality of bowed wooden ribs, the 20 lower of said ribs being longitudinally scarfed from the rear end thereof and upwardly extended to bear against the upper of said ribs at different points in the length thereof; and means for rigidly uniting the 25 forward section of said ribs.

In testimony whereof I have signed my name to this specification in the presence of two subscribing witnesses.

JOHN ANDERSON.
